UNITED STATES PATENT OFFICE

125,769

DESIGN FOR AN ELEVATED TANK

George T. Horton, Chicago, Ill., assignor to Chicago Bridge & Iron Company, a corporation of Illinois

Application October 7, 1940, Serial No. 95,674

Term of patent 14 years

To all whom it may concern:

Be it known that I, George T. Horton, a citizen of the United States, residing at Chicago, in the county of Cook and State of Illinois, have invented a new, original, and ornamental Design for an Elevated Tank, of which the following is a specification, reference being had to the accompanying drawing, forming a part thereof, in which:

The figure is a perspective view of an elevated tank showing my new design.

I claim:

The ornamental design for an elevated tank, as shown.

GEORGE T. HORTON.
